Primary Examiner — Vy N Koenig(74) *Attorney, Agent, or Firm* — Rao DeBoer Osterrieder, PLLC; Dileep P. Rao(57) **CLAIM**

The ornamental design for a container for storing biological material, as shown and described.

DESCRIPTION

FIG. 1 is a right side elevation view of a container for storing biological materials showing our new design.

FIG. 2 is a front elevation view thereof.

FIG. 3 is a left side elevation view thereof.

FIG. 4 is a rear elevation view thereof.

FIG. 5 is a top plan view thereof; and,

FIG. 6 is a bottom plan view thereof.

The broken lines in the drawings depict portions of the container for storing biological material that form no part of the claimed design.
